UNITED STATES PATENT OFFICE.

WILLIAM H. GADE, OF IOWA FALLS, IOWA.

CONTROL MECHANISM FOR EXCAVATING-MACHINES.

1,265,443.

Specification of Letters Patent.

Patented May 7, 1918.

Application filed June 25, 1914. Serial No. 847,339.

To all whom it may concern:

Be it known that I, WILLIAM H. GADE, a citizen of the United States, and resident of Iowa Falls, in the county of Hardin and State of Iowa, have invented a certain new and useful Control Mechanism for Excavating-Machines, of which the following is a specification.

The object of my invention is to provide a control mechanism for excavating machines of compact and convenient arrangement.

A further object of my invention is to provide such a mechanism capable of being operated by a single person without requiring such person to move from a predetermined position in order to operate the mechanism actuating the many devices with the excavating machine.

A further object of my invention is to provide novel means for operating certain of the clutch mechanisms whereby the engineer or operator may control certain of the movements of the excavating machine by pushing with his knee, if he be in sitting position or by swaying his body, if he be standing up.

With these and other objects in view, my invention consists in certain details in the construction, combination and arrangement of the various parts of the device, whereby the objects contemplated are attained, as hereinafter more fully set forth, pointed out in my claims and illustrated in the accompanying drawings, in which:

Figure 1 shows a top or plan view of one form of my invention.

Fig. 2 shows an end view of certain of the parts thereof.

Fig. 3 shows a side view of the parts shown in Fig. 2.

Fig. 4 shows an elevation of my improved clutch mechanism, which is used in connection with my invention.

Fig. 5 is a vertical, sectional view taken on the line 5—5 of Fig. 4, and

Fig. 6 is a horizontal, sectional view taken on the line 6—6 of Fig. 5.

Referring to the accompanying drawings, I have used the numerals 13 and 15 to indicate generally the end and side members of the supporting frame upon which my invention is installed. Journaled transversely of the frame is the main shaft 55 whereon the various elements of my invention are mounted. Adjacent to and parallel with the shaft 55 a second shaft 56 is journaled

to the frame, one end of the shaft 56 being supported by one of the pair of intermediate frame members or braces 24. A gear 70 is fixed to the shaft 55 and a pinion 69 is fixed to the shaft 56 in position to mesh with the gear 70 whereby rotation may be imparted from the latter shaft to the former shaft. Secured to the shaft 56 is a pulley wheel 57 adapted to be connected to any suitable source of power.

It will be understood that the braces 24 are disposed adjacent to the center of the supporting frame and are adapted to support a suitable platform (not shown) where the operator may either sit or stand. For this reason each of the devices hereafter described must be so placed and connected that they may be operated by the shaft 55 and yet the operative connections between such device and the shaft must be so arranged that they may be actuated by the operator without his having to move from position between the braces 24.

Rotatably mounted on the shaft 55 at opposite sides of the braces 24 are drums 73 and 74. It may be mentioned that the drum 74 is only partially visible on the Fig. 1 of the drawings because of being somewhat obscured by a second drum placed thereabove, which will be hereafter described. At one side of the drum 74 spaced therefrom a second drum 75 is rotatably mounted on the shaft 55. It will be understood that the drums 73 and 74 are designed to be actuated to retract cables whereby the boom of the excavating machine may be moved from side to side. The drum 75 is designed to carry another flexible device, which may extend over a pulley on the end of the boom and operate independently of the bucket for lowering large tile or the like into the ditch, which has been made by the excavating machine. Adjacent to the drum 75 a sprocket wheel having a hub 64 is rotatably mounted on the shaft 55, which is designed to be operatively connected with a fourth drum 66, the latter being designed to carry a cable connected with the bucket on the boom whereby the latter may be drawn toward the excavator thereby scraping dirt into the bucket. In the present form of my device, I have shown the connections between the drum 66 and said sprocket as consisting of a shaft 62, which is spaced above and parallel with the shaft 55 and at one end has the sprocket 63 connected by a

from the interior of the range 71. In the
40 side of each arm 79 adjacent to the drum or
sprocket as the case may be, the notches 81
are cut thereby forming shoulders and a slot
wherein the friction block 82 may be slid-
ably received. The use of the friction blocks
45 82 sliding in the slot formed by the notch 81
permits the adjustment to be made to take
care of any wear upon the permanent mem-
bers by changing the thickness of the
blocks 82.
50 Extending inwardly from each of the
friction shoes 80 are a pair of brackets 83,
provided with openings in alignment with
each other, in which are mounted rods 84.
Pivotedly mounted on the rods 84, near each
55 of the brackets 83, is a link 85, extending in-
wardly. Slidably mounted on the shaft ad-
jacent to each hub or collar 78 is a collar
86 which is yieldingly held away from the
hub 78 by means of springs 87. The inner
60 ends of the links 85 are pivoted to the sides
of the collar 86 at points in line with the
middle of the shaft on which said collar is
mounted.
It will thus be seen that each friction shoe
65 is connected with the collar 86 by a pair of

drums 73, and 75, there is mounted on the
shaft adjacent to the collar 86 a collar 93. 105
For operating the collars 93 adjacent to the
sprockets 71 and the drum 75, I have pivoted
to the frame levers 94 and 95, formed in
which are elongated slots 96 which receive
pins 97 on the collars 93. For operating said 110
collar 93 adjacent to the drums 73, I have
provided levers 97^a, having bifurcated arms
fulcrumed at one end on the frame and cen-
trally pivoted to short links 98 which are
pivoted to the collar 93 on opposite sides 115
thereof.
For operating said levers 97^a I have pro-
vided the following mechanism: Connecting
the ends of the levers 97^a, opposite the places
where they are pivoted to the frame, is a 120
transverse connecting member 98^a. Bolted
on the platform are pairs of brackets 99,
each pair being arranged in alignment lon-
gitudinally of the platform and the mem-
bers of each pair being spaced from the 125
members of the other pair laterally in align-
ment therewith. Pivoted to the respective
pairs of brackets 99 and detachably mounted
thereon are the lower ends of two upright
arms 100. The upper ends of the arms 100 130

- are connected by a longitudinal member 101. Above the members 101 are bars 102, detachably secured to the members 101 by means of brackets 103 bolted to said bars 5 and in which said members 101 are rotatably mounted. Mounted in the ends of the bars 102 are bolts 104 which are rotatably extended through holes in the members 98 and are held in position by means of nuts 105.
- 10 The members 102 are so located with relation to each other that the operator of the machine may stand between the two members 102 and by leaning one way or the other may move them with his body, thereby operating the respective clutches whereby the drums 73 and 74 are thrown into gear with the shaft 55. Suitable detachable bearings 20 are arranged in alinement with each other and rotatably mounted in said bearings 20 is a transverse rock shaft 106 having at one end a lateral extension 107 pivoted to the lever 92, which operates the clutch for the sprocket 64. Formed on the opposite end of the rock shaft 106 is a lateral extension 108, on the end of which is an upward extension 109, extending in a position where it would be readily accessible to an operator who is between the members 102. The extension 109 and the parts coöperating therewith are so arranged that rearward movement of the extension tends to throw the clutch into engagement. It will be seen that by this arrangement the operator will pull toward him the extension 109 when he desires 30 to have the bucket on the boom drawn toward him to scrape up the dirt thereby tending to make the motion, which controls the movement of the boom natural.
- In the practical operation of my device, 40 it will be understood that the parts herein before described are designed to be attached to the frame work of a grading or excavating machine of the type, which is designed to be taken apart when it is being shipped.
- 45 For this reason I provide the unitary arrangement herein shown, so that the controlling means may be removed from the machine and shipped as a unit. It will also be noted that the arrangement of the controlling levers relative to the position of the operator is such that the movement made by the operator follows the direction of the movements, which he intends the moving parts of the excavating machine to take.
- 50 For instance, if he desires to move the boom to the right, he will lean against or push on the right hand bar 102 to thereby engage the proper clutch to throw the boom to the right. If it is desired to pull the bucket up, he 55 pulls the lever 92 toward him. Should it be desired to draw the bucket toward the machine for scraping dirt into the bucket, he draws the extension 109 toward him. The lever 95 is also so placed relative to the position of the operator that he does not need to
- lean far to reach it to operate the secondary hoisting device upon the boom. Adjacent to the lever 95 the hand lever 127 is mounted, which is in turn operatively connected with the bracket 126 whereby the unwinding of 70 the drum 75 may be retarded. The lever 94 is not placed adjacent to the operator as there is no necessity for him to operate the balance of the machine at the time he operates this lever as this lever controls only the 75 movement of the entire excavator over the ground. It will be seen from the foregoing that I have provided a convenient arrangement of controlling devices whereby a single person may readily operate without unnecessary exertion all the various parts of an excavating machine and I have also provided a clutch device to coöperate with my controlling means in imparting power from the main power shaft to the various drums. 80
- 85 Some changes may be made in the details of the construction of my excavating machine without departing from its essential features, and it is my intent to cover by this application any such changes which may 90 be included within the scope of the following claims:
- I claim as my invention:
1. In a device of the class described, a main shaft, a pair of spaced drums rotatably mounted thereon, means for operatively connecting said drums with the shaft, a lever operatively connected with each of the last described means, a bar pivoted at each end to one of said levers, a pair of spaced 95 parallel bars extended laterally from the intermediate portion of said first described bar, the parts being so disposed that the operator may move the first described bar longitudinally in either direction by placing 100 himself between the last two described bars and pushing against one of them whereby the drums may be selectively rendered operative or both drums may be rendered inoperative. 105
- 110 2. In a device of the class described, a main shaft, means for imparting rotation thereto, a pair of drum devices rotatably mounted upon the shaft, a clutch device adapted to operatively connect each drum 115 with the shaft, a lever adapted to move each clutch device into and out of operative engagement, the levers being so arranged that moving them in similar directions will render one clutch inoperative and the other operative and being so arranged that in one position both clutches will be inoperative, a bar extended between the ends of said levers, a pair of upwardly extending frames adapted to be pivotally connected at their lower 120 edges with a support and having their forward upper ends operatively connected with said bar whereby an operator standing positioned between said frames may render either clutch operative by pushing away 125 130
